HIRAM NORTON, OF DELTON, WISCONSIN.

Letters Patent No. 75,569, dated March 17, 1868.

IMPROVEMENT IN DOOR-LOCKS.

The Schedule referred to in these Letters Patent and making part of the same.

TO ALL WHOM IT MAY CONCERN:

Be it known that I, HIRAM NORTON, of Delton, in the county of Sauk, and State of Wisconsin, have invented a new and improved Combination Door-Lock; and I do hereby declare that the following is a full, clear, and exact description thereof, which will enable those skilled in the art to make and use the same, reference being had to the accompanying drawings, forming part of this specification, in which—

Figure 1 is a side view of the internal mechanism of the lock.

Figure 2 is a cross-section of the same through the line $x x'$, fig. 1.

Figure 3 is a detail section of the bolts, showing the principle of the key's action.

Similar letters of reference indicate corresponding parts.

This invention refers to an improved method of constructing combination-locks for doors, drawers, &c., and consists of two or more independent tumblers, which are hung by a pivot-pin, at a middle point, and are operated by a very small key. These latches catch into notches on the bolt, thus preventing the movement of the latter, as will be more fully set forth.

In the drawings, A is a metallic plate, having a top, bent up as shown, and sides C C. The front plate of the lock is removed, it being simply a plate screwed on in the usual way. The latches are shown at α , being pivoted to the plate A by a screw or pin, m.

The ends of the latches are bent downwards, as shown at $n n'$, for the purpose of catching into the notches $n n''$, on the bolt B. The latches, thus hung on a central pivot, are lifted by the insertion of a small narrow key into a slot in the key-hole stud o, which projects from the plate A, under and in contact with the latches, at some point near to their central pivot, as shown in the drawing.

The key is simply a narrow metallic vane, fitting snugly in the slot in the key-hole stud, and having its upper or actuating surface curved in any desired manner, according to the curve of the under side of the latches at the point where the key impinges against them, and the key once fitted to this curve, no other will lift them, for the slightest deviation of the false key from the proper curve will fail in freeing the bolt from the latches, for it will not lift the end, n' , of one or both of them, or it will lift one or both of them too much, and thus depress the end, n'' , into the notch n''' , which will still prevent the bolt from being withdrawn. This bolt traverses in suitable slots in the side-pieces C C, and is held in place by studs v v, cast or set into the plate A, all as shown.

When the bolt is freed from the latches, it is thrown in or out by a knob, N, having a pin, r, projecting from the arbor of the knob, and which pin strikes against the pins e e, on the bolt, as the knob is turned right or left, whereby the bolt is moved in either direction.

Springs s s furnish a resisting tension, to return the ends n' back into the notch n when the key is withdrawn.

The key, acting upon the latches at a point near their centres of movement, requires to be an exact fit, for the slightest variation in the shape of its curve would produce a multiplied effect at the ends of the latches, and this feature, together with the smallness of the key-hole, renders it very difficult, if not impossible, to fit a false key, or to raise the latches with picks or other instruments. The fitting of a key by guess would be hardly possible.

The location of the key-hole near the centre of movement of the latches admits of the employment of a very small key and key-hole, and the smallness of the latter would render the introduction of powder, for blowing off the lock, difficult, or the employment of picks, to open the lock, or the introduction of any article whereby to take an impression of the lock, also difficult, if not wholly impossible.

By keeping the key always inserted in the lock, and providing a spring to urge the bolt outward, the same can be used as an ordinary latch-bolt for doors.

If a number of latches are used, the lock becomes proportionately difficult to open by false means, and if the latches are sufficiently multiplied, the lock can be made available for safe-locks. A lock with six latches would be almost impossible to pick, or fit with a false or otherwise than with the proper key. It is simple, cheap, and generally available.

I am aware that combination-locks, opened by small curved keys, have been made, and do not claim such broadly; but

What I claim, and desire to secure by Letters Patent, is—

The employment of two or more tumblers, α , having their centre of movement at or near their middle points, and having their ends catching into notches $n n''$, on the bolt B, all substantially as and for the purpose shown and described.

HIRAM NORTON.
